JAMES H. DONALDSON, OF CHICAGO, AND BENJAMIN T. LEWIS, DECEASED, LATE OF CHICAGO, ILLINOIS, BY MINNIE C. LEWIS, EXECUTRIX, OF LA GRANGE, ILLINOIS.

AUTOMATIC RELEASE MECHANISM FOR VESTIBULE-CURTAINS.

1,105,261.

Specification of Letters Patent.

Patented July 28, 1914.

Original application filed April 17, 1911, Serial No. 621,667. Divided and this application filed May 9, 1914. Serial No. 837,385.

To all whom it may concern:

Be it known that we, JAMES H. DONALDSON and BENJAMIN T. LEWIS, deceased, citizens of the United States, residing at Chicago, in the county of Cook and State of Illinois, have invented new and useful Improvements in Automatic Release Mechanism for Vestibule-Curtains, of which the following is a specification.

10 Our invention has for its object to produce a simple and reliable mechanism for automatically disconnecting the free ends of car vestibule curtains whenever the cars to which they are attached are drawn apart an 15 abnormal distance, thus preventing injury to the curtains and permitting them to roll up automatically out of the way.

The various features of novelty whereby our invention is characterized will herein 20 after be pointed out with particularity in the claims; but, for a full understanding of our invention and of its objects and advantages, reference may be had to the following 25 detailed description taken in connection with the accompanying drawings, wherein:

Figure 1 is a longitudinal vertical section through the adjoining vestibules of two passenger cars showing our improved curtain mechanism in place; Fig. 2 is an enlarged 30 view of a fragment of the edge of the curtain adjacent to the handle, parts being broken away to show the interior; Fig. 3 is a section on line 3—3 of Fig. 2; and Fig. 4 is a view similar to Fig. 2 illustrating a 35 modification.

Referring to the drawings, 1 and 2 represent the vestibule door posts on the adjacent ends of two cars.

3 is a curtain mounted in any suitable way 40 on the post 1, preferably on the usual spring roller, and adapted to be drawn across the space between the two posts and attachably fastened at its free edge to the post 2; thus forming a cover across the inner side of the 45 diaphragm, 4, and protecting passengers from contact with the diaphragm.

It sometimes happens that cars are uncoupled, either accidentally or otherwise, and are drawn apart while the free end of 50 the curtain is still fastened. When this occurs, unless some means is provided for automatically releasing the curtain, the latter is of course torn and destroyed. In accordance with our invention we have provided a 55 simple and effective means which will cause

the curtain to detach itself automatically and roll up whenever the cars are drawn apart a predetermined distance. To this end we prefer to form the stiffening member 5 along the free edge of the curtain of a 60 tube within which is a vertically-movable bar or other tripping device, 6, suspended from a chain or cable 7 which passes up over a pulley or roller, 8, at the upper outer corner of the curtain and then back to the 65 post on which the curtain is mounted; the end of the chain being fastened to the post as indicated at 9. The members 6 and 7 are made of such length that when the curtain is completely wound up or retracted in its 70 casing, the chain or cable is housed within the tubular stiffening member and supports the lower end of the tripping member 6 at or above the bottom of the stiffening member. With this arrangement, as the curtain 75 is drawn out, the flexible member must be withdrawn from the tubular stiffening member at the rate at which the curtain is being unwound, the bar or other tripping device consequently being lifted. We make use of 80 this movement of the member 6 to unfasten the free end of the curtain automatically in case the cars are drawn apart before the free end of the curtain is unfastened. This may conveniently be accomplished by the 85 construction shown in Figs. 2 and 3 and that shown in Fig. 4.

Referring first to Figs. 1, 2 and 3, it will be seen that on the post 2 of the car is a hook or catch, 10, adapted to receive a handle on the free edge of the curtain. The handle is made of a bar or tube 11, hinged as at 12, at its upper end to a bracket or casting, 13, fastened to the stiffening tube of the curtain. The lower end of the member 11 abuts against the outer end of an arm 14 on the casting or bracket. The arm 14 is made hollow and contains a spring-held dog, 15, whose nose, 16, is adapted to engage with the lower end of the member 11 and hold it locked against the arm 14. The rear end, 17, of the dog projects through a slot 18 in the tube 5 and lies in the path of a head 19 on the lower end of the tripping device 6. It will be seen that if the 105 tripping device is lifted far enough, the head 19 will strike the tail of the dog and will swing it out of engagement with the handle member 11 so that the latter member is free to swing on its hinge. The parts 110

are so proportioned that when the curtain is drawn out as far as it normally will be when in use, the head 19 lies in close proximity to the dog and consequently, in case 5 the cars part and thus begin to draw the curtain out farther, the dog will be tripped and the handle will be automatically freed from the catch before the curtain can be damaged.

10 The arrangement shown in Fig. 4 differs from that in Fig. 2 only in the details of the handle, the curtain with its stiffening tube and tripping bar being the same in both cases. In Fig. 4 the handle is in the 15 form of a bar, 20, having at its upper end a chain or other flexible member 21 which is fastened to a suitable bracket or casting, 22, on the curtain. At the lower end of the member 20 is a second flexible member, 23, 20 provided with a resilient catch projecting through the slot 18 in the stiffening tube and adapted to be engaged by the head 19 on the tripping device in emergencies. In the arrangement shown the spring catch is 25 made in the form of a link, 24, having two separated arms, 25 and 26. The end of the arm 26 is folded back as indicated at 27 so as to transform this arm into a hook. The parts are so proportioned that the tension 30 of the spring catch tends to spread the arms 25 and 26 apart, so that these arms must be pressed toward each other in order to permit them to be inserted through the opening 18. When the ends of the arms 25 35 and 26 have been inserted through the opening 18 and are released, the tension spreads them apart until they lie in opposite ends of the opening 18 and the part 27 serves as a shoulder engaging with the interior of 40 the stiffening tube just below the opening. In this arrangement the inner end of the arm 26 lies in the path of the head 19 on the tripping device so that when, in an emergency, the head rises, the arm 26 is 45 lifted until the part 27 clears the wall of the stiffening tube and is free to move out through the opening 18. If at this time the cars are being drawn apart, the spring catch simply draws out and allows the handle 50 member 20 to yield and release itself from the hook.

While we have illustrated and described only two preferred forms of our invention, we do not desire to be limited to the exact 55 structural details thus illustrated and described, but intend to cover all forms and arrangements which fall within the terms employed in the definitions of our invention constituting the appended claims.

60 We claim:

1. In combination, a car vestibule door post, a curtain roller mounted on said post, a device including a catch on the free end

of the curtain for securing it to the door post on an adjoining car, a flexible member connected at one end to the post on which the curtain roller is mounted at a point above the curtain, a guide on the free end of the curtain over which said flexible member passes, and means on said flexible member 65 for engaging with said catch and tripping the same when the curtain is drawn out a predetermined distance.

2. In combination, a car vestibule door post, a curtain roller mounted on said post, 75 a device on the free end of the curtain for securing it to the door post on an adjacent car, a catch for maintaining said device in an operative position, a flexible member connected at one end to the door post on which 80 the curtain roller is mounted, a guide at the free end of the curtain over which said flexible member passes, and means on said flexible member for engaging with said catch and tripping the same when the curtain is drawn 85 out a predetermined distance.

3. In combination, a car vestibule door post, a curtain roller mounted on said door post, a curtain on said roller, said curtain having a tubular stiffening member extending along its free edge, a flexible member secured to the aforesaid door post and extending into said tube, a securing device at the free end of the curtain for connecting the curtain to the vestibule door post of an adjacent car, and means on said flexible member 95 for releasing said securing device.

4. In combination, a car vestibule door post, a curtain roller mounted on said door post, a curtain connected at one end to said 100 roller, a tubular stiffening member along the free edge of the curtain, a flexible member secured at one end to said door post and extending at its other end into said tubular member, a fastening device for the free end 105 of said curtain including a catch projecting into said tubular member adjacent to a portion of said flexible member, and means on said flexible member for tripping said catch when the curtain is drawn out a predetermined 110 distance.

In testimony whereof we sign this specification in the presence of two witnesses.

JAMES H. DONALDSON.
